(57) CLAIM

We claim the ornamental design for a coin dispenser, as shown and described.

DESCRIPTION

FIG. 1 is a perspective view of a coin dispenser, showing our new design;

FIG. 2 is a front elevational view thereof, the rear elevational view, the left side elevational view, and the right side elevational view being identical to this Figure; and,

FIG. 3 is a top plan view thereof, the bottom plan view being identical to this Figure.

1 Claim, 2 Drawing Sheets

FIG. 3.
